MOUNTING FOR TYPEWRITERS OR OTHER MACHINES ON CABINETS

Floyd H. Bloomstran, Jamestown, N. Y., assignor to Art Metal Construction Company, Jamestown, N. Y.

Application September 22, 1948, Serial No. 50,606

16 Claims. (Cl. 312—29)

1 This invention relates to improvements in desks or cabinets having typewriters or other machines mounted on supports in such manner that the machine may be supported in an inoperative position within a compartment of the desk or cabinet or may be moved out of the compartment and then swung upwardly into an operative position for use.

One of the objects of this invention is to provide a mounting of improved construction for a typewriter or other machine in which the supporting structure is so arranged as to provide ample stability and freedom from vibration of the desk or cabinet on which the machine is mounted. Another object is to provide improved means for moving the machine while in vertical or hanging position into and out of the compartment in which it is housed when not in use. Another object is to provide mechanism for mounting a machine on a cabinet, which mechanism can be more readily assembled and placed in the cabinet. A further object is to provide mechanism for preventing movement of the machine into the compartment except when in its lowest position and when in position to engage a guide rail for preventing swinging of the machine while in the compartment.

It is also an object of this invention to provide a carriage of improved construction for moving the machine into and out of its compartment; also to provide guide means of improved construction for guiding the carriage in its movement into and out of its compartment. A further object is to provide means for preventing the machine from swinging when in said compartment and for preventing the moving of the machine into its compartment except when properly engaged with the means for preventing the swinging. Another object is to provide means of improved construction for firmly securing the machine supporting frame in its upper or operative position.

Other objects and advantages of this invention will appear from the following description and claims.

In the accompanying drawings which illustrate by way of example one embodiment of this invention:

Fig. 1 is a sectional elevation through a desk pedestal or compartment showing a machine-supporting mechanism embodying this invention in the position which it occupies when the machine is not in use.

Fig. 2 is a similar elevation showing the supporting mechanism in the position in which the

2 machine has been drawn forwardly out of the pedestal or compartment of the desk, and before the machine is swung upwardly into its operative position.

5 Fig. 3 is a front elevation of the mechanism shown in Fig. 2, on an enlarged scale.

Fig. 4 is a fragmentary, transverse, sectional elevation thereof, on line 4—4, Fig. 1.

Fig. 5 is a top plan view of the mechanism and 10 a portion of the desk pedestal or compartment, showing the parts in the position which they occupy when the machine is in its operative position.

Fig. 6 is a fragmentary, sectional elevation 15 thereof, on line 6—6, Fig. 5.

Fig. 7 is a fragmentary, sectional plan view thereof, on line 7—7, Fig. 2.

Fig. 8 is a transverse, sectional plan view 20 thereof, on line 8—8, Fig. 3.

Fig. 9 is a fragmentary sectional view thereof, 25 on line 9—9, Fig. 8.

Fig. 10 is a fragmentary sectional elevation thereof, on line 10—10, Fig. 5.

Fig. 11 is a top plan view, partly in section, of 25 the structure shown in Fig. 10.

The machine supporting structure may be applied to any suitable or desired compartment or container for the machine and, in the construction illustrated, the mechanism is mounted in a 30 pedestal of a desk including an upright, outer side wall 10, an opposite side wall 11, a rear wall 12, and a bottom wall 13. The pedestal has a front wall 14 which may be closed by means of a door 15, including a suitable handle 16 and

35 mounted on hinges 17. The outer wall may be reinforced in any suitable manner, for example, by means of a pair of upright frame members 18 and 19 of Z-shape in cross section, which may be welded or otherwise suitably secured to the outer side wall 10 and the lower ends of which may be secured to two lower reinforcing members 20 secured to the bottom wall 13. Similarly, the inner side wall 11 may be reinforced by means of one or more reinforcing members 22, one of which is

40 shown in Fig. 5, and which may also be of Z-shaped cross section. The parts of the desk pedestal or cabinet may, of course, be of other suitable or desired structure.

The typewriter or other machine may be suitably secured in any well known manner to a 45 table top or plate 25 which, in turn, is mounted on a machine supporting frame of any desired construction, that shown including a pair of structural members 26 and 27 which may, for example, be of channel shape in cross section and

connected at their inner ends by means of a cross member 28, and at their outer or front ends to a transversely extending reinforcing bar 29. The members 26, 27, 28 and 29 may be secured together in any suitable manner, such for example, by welding, to form a rigid frame to which the machine table top or platform 25 is suitably secured, and if desired, one or more cross braces (not shown), connecting the members 26 and 27 may be provided, to provide a strong and rigid machine supporting structure. The outer edges of the table top may be flanged downwardly to further increase the rigidity of the structure and to protect the user of the machine from coming into contact with sharp or rough edges. 30 represents a hand rail or bar secured at its ends to the table top at the outer end thereof to facilitate the swinging of the table into and out of its operative position.

The supporting platform or table top 25 and the supporting frame on which it is mounted together with the machine mounted on the table top are supported on a carriage which is mounted at one side of the compartment in the pedestal or cabinet to move lengthwise thereof. The supporting frame is hingedly mounted on the carriage to swing to and from a position in which the same is in a substantially vertical or hanging position shown in Figs. 1 and 2 and into a horizontal position shown in Fig. 5, in which the machine is in operative relation to an operator. The carriage is of truss or cantilever form, having a substantially horizontally extending rigid bar 32 which is rigidly secured to and extends forwardly from an upright plate or truss member 35 which is guided for movement lengthwise of the compartment. In the particular construction shown, the transversely extending frame members 28 and 29 have their ends pivoted to the bar 32 in any suitable manner, for example, by means of a stud or pin 33 welded or otherwise rigidly secured to the frame member 28 and formed to fit into a hole drilled in the rear end of the bar 32, and a pivot screw 34 passing through a hole in the end of the transverse frame member 29 and having a threaded engagement in a hole in the front end of the slidable bar 32.

In order to provide ample stability of the desk or container for the machine when a machine, which may be fairly heavy, is supported beyond the front edge of the desk or container, it is desirable to arrange the supporting mechanism for the machine as low as possible within the pedestal or container, thus increasing the stability of the desk and also reducing the vibration of the desk by having the rear legs of the desk resting firmly on the floor. A carriage of a cantilever shape as shown is desirable for this purpose, since the rails or tracks on which the carriage moves and which support the weight of the carriage and the parts mounted thereon may then be arranged well below the upper portion of the pedestal or cabinet on which the machine is supported. The lower portion of the substantially upright plate or truss member 35 is suitably mounted to roll or slide on a supporting rail 36. The plate 35 is somewhat truss-shaped, having a part 37 extending upwardly and forwardly from the lower edge thereof and is preferably reinforced or stiffened by means of integral flanges 38 and 39 formed on the front and rear edges thereof. Consequently, as shown in Fig. 2, when the machine is drawn forwardly into its operative position, the greater part 10 of the plate 35 will still be within the pedestal

or container, thus providing increased stability of the desk or container.

Any suitable or desirable means may be provided for supporting this truss plate on the rail 36 in such a manner that it may move lengthwise of this rail. In the construction shown for this purpose, the rail 36 is provided with upper and lower V-shaped edge portions 40 and 41, Figs. 2, 3 and 4, and the truss plate 35 has a pair of upper rollers 42 mounted to rotate on bearing pins 43 rigidly secured to the truss plate 35, these rollers operating on the V-shaped upper portion 40 of the track 36. Another pair of rollers 45 is mounted on the plate 35 in such a manner as to engage the lower V-shaped portion 41 of the rail 36. These rollers are spaced apart horizontally sufficiently to provide a secure bearing of the truss plate on the rail and to avoid lost motion between the truss plate 35 and the rail, so that the supporting plate or table top 25 for the machine may be securely held in horizontal position, the lower rollers 45 being preferably adjustably mounted on the truss plate 35. The bearing pins 46 for the lower rollers 45 thereof extend through upright slots on the truss plate and adjusting screws 47 are provided which have a threaded engagement with a reinforcing flange 48 formed by bending over the lower edge of the truss plate 35. The upper ends of these screws may engage the bearing pins 46 or spacing bushings 49 extending about the same. By means of this construction, the lower rollers 45, when the bearing pins 46 are loosely clamped to the truss plate 35, may be urged upwardly into positions in which they will press against the lower V-shaped portion 41 of the track or rail 36 to the desired extent so as to provide proper rolling contact without play between the truss member 35 and the track or rail 36. When the rollers are properly adjusted, the bearing pins 46 are tightly secured to the truss plate and the adjusting screws may be secured by means of lock nuts in their correct positions. Any other means for accomplishing this purpose may be employed, if desired. The truss member or plate 35 may be provided with a longitudinally extending channel-shaped offset portion 50 to provide ample clearance between this plate and the rail 36.

In order to prevent the truss plate 35 from rolling beyond the end of the track or rail 36, stop means of any suitable type may be provided, such for example as an angle-shaped member 52, see particularly Fig. 7, secured to the offset portion 50 of the truss plate 35 and having a leg extending through a hole or opening in the offset portion 50, into position to engage a resilient or flexible bumper 53 mounted on and secured to a part of the rail 36. The side wall of the rail may have a projection 54 partly punched out therefrom and bent over to form a stop for the resilient bumper member 53. By means of this construction, movement of the truss plate beyond the end of the track or rail 36 is prevented.

The rail 36 is mounted to slide to a certain extent within the pedestal or container so that the front end of this rail may extend slightly beyond the front face of the cabinet or desk when the machine is in its operative position. Any suitable mounting to provide such endwise movement of the rail 36 may be provided, and in the construction illustrated, a stationary guide track 56 is provided which is bolted or otherwise secured to the upright frame members 18 and 19. In the particular construction shown, rigid rein-

forcing plates or straps 57, Figs. 2, 3 and 4, are provided to which the stationary guide track 56 is secured by any suitable means, such as bolts or screws 58 and which plates are secured to the frame members 18 and 19 for reinforcing portions of the same. The reinforcing plates are preferably secured to the frame members by bolts 59.

The stationary guide track has a flat bearing surface secured to the plate 57, and a pair of trough or V-shaped extensions 60 and 61, the outer surfaces of which form recesses for balls or rollers 62 and 63. The inner surfaces of the angle-shaped members 40 and 41 of the rail 36 also cooperate with the rollers or balls 62 and 63 so as to permit rolling contact between the rail 36 and the stationary track 56.

Suitable stops are also provided for limiting the extent to which the rail 36 may move relatively to the stationary track 56. For this purpose, in the construction shown, see Fig. 7, a stop 65, which may be similar in construction to the stop 52, is arranged on the stationary rail 56 and has a part which extends through an aperture therein into a position to engage a resilient stop or bumper 66 mounted on an inwardly projecting ear or lug 67 partly stamped out of the rail 36 to limit the outward movement of the rail. This stop 65 may also be used to engage with another bumper 68 mounted on an integrally formed lug 69 of the rail 36 to limit the extent to which the rail 36 may move into the compartment, i. e., toward the rear wall 12 of the cabinet or desk. Any other means may, of course, be provided for limiting the movement of the rail 36 relatively to the stationary track 56.

The balls or rollers 62 and 63 are arranged in suitable cages 70 of approximately C-shape as clearly shown in Figs. 3 and 4. Each cage has an upper arm with an aperture for the upper ball 62 and a lower arm for the ball 63. Means are provided to limit the movement of these balls or rollers to keep them in their correct locations relatively to the rail 36 and track 56. For this purpose, projections 71 of any suitable type may be provided to restrict the extent to which the balls may roll on the stationary track 56. These projections may be formed by the heads of pins arranged in holes in the parts 60 and 61 of the track 56.

As a result of the construction described, it will be obvious that when it is desired to move the machine outwardly from the compartment, the plate 35 will first roll on the rail 36 until the stop 52 engages the bumper 53, whereupon the rail 36 will move lengthwise of the stationary track on the balls or rollers 62 and 63 until the bumper 66 moves into engagement with the stationary stop 65 on the track 56. These various stops are so positioned that when both stops are in engagement with their bumpers, the truss plate will have been withdrawn to the forward limit of its movement. Upon return of the plate with the machine supported thereby into the pedestal or container, the plate will roll along the rail 36 until the stop 52 on the truss plate engages a stop or bumper 73 mounted on the rail 36, whereupon the truss plate and rail will move together into the inner position of these parts, at which time the bumper 68 on the rail 36 will engage stop 65 on the stationary track 56, and thus prevent any part of the mechanism from striking the back wall of the desk or cabinet. Any other means for limiting the movement of these parts may be employed, if desired.

Additional means must, of course, be provided for holding the carriage including the truss plate 35 in upright position, and the bar 32 in correct relation to the desk or cabinet, and for this purpose a guide 75 in the form of a rail of substantially inverted U-shape is secured to offset portions 76 of the upright reinforcing plates or strips 57. The bar 32 of the carriage is provided with an upwardly extending stud or bearing pin 77, see particularly Figs. 2 to 4, on which a roller 78 is mounted to roll between the two downwardly extending flanges of the U-shaped guide rail 75. This roller will guide the rear end of the bar 32, and additional rollers 79 are provided for engaging opposite sides of this bar during its movement into and out of the compartment. These rollers may be suitably mounted on the guide rail 75 or any fixed part of the desk or cabinet, and in the construction shown by way of example, a reinforcing member 80 for the front of the guide rail 75 is provided, which may be of inverted U shape and fitted over and secured to the front end of the guide rail, and the pivots for the rollers 79 may be welded or otherwise secured to this reinforcing member. One flange of the reinforcing member 80 preferably extends forwardly beyond the guide rail 75 and may be secured to an inwardly extending flange 81 of the door opening of the front wall of the cabinet, for example, by means of a bolt 82. The rollers 78 and 79 also serve to maintain the bar 32 and truss plate 35 secured thereto in alignment with the rail 36 and track 56 during the lengthwise movement of the bar into and out of the pedestal container. Any other means for guiding the upper portion of the carriage for movement lengthwise of the compartment may be provided.

Means are also provided for holding the table top and supporting mechanism thereof in vertical or fully swung down position when the machine is to be housed in the pedestal or compartment, so that portions of the machine cannot be damaged by striking the wall 11 or the edge of the door opening in the front wall 14. For this purpose, the frame member 26 is provided with a roller 83 suitably journaled on a bearing pin secured to the frame member 26 and so positioned as to cooperate with a suitable guide during the movement of the carriage into and out of the compartment. In the construction illustrated, this roller bears against that surface of an upright flange of the angle bar or angle-shaped member 84 which faces the side wall 10 of the cabinet. This angle-shaped member may be suitably secured to the lower ends of the reinforcing plates 57. For example, the reinforcing plates may have their lower edges bent over, as shown at 85, Fig. 2, and welded or otherwise secured to the angle bar or guide member 84. Consequently, when the machine supporting frame is swung into vertical or hanging position, as shown in Fig. 2, the roller 83 can engage the upright flange of the angle bar 84 and thus hold the pivoted machine-supporting frame from swinging about its pivots 33 and 34 until the roller 83 passes beyond the front end of the flange of the angle bar 84.

Means are also provided for preventing the machine from being moved into the pedestal or compartment unless the roller 83 is in engagement with the surface of the flange of the angle bar 84 which faces the side wall 10. This may, for example, be accomplished by providing a leaf spring 87, Figs. 2 and 8, one end of which is secured by means of one of the bolts 59 to one

of the reinforcing strips 57, and the other end of which normally extends into the path of movement of a part of the truss plate 35, for example, the lower flange 48 of this plate. The spring 87 may be held in correct position by means of a pair of lugs or projections 89 formed on the adjacent reinforcing plate 57. Consequently, normally the spring 87 would prevent movement of the truss plate 35 along the rail 36. However, the inner end plate 28 of the supporting structure for the table top is so arranged as to move into engagement with the spring 87 when the machine supporting frame has been swung into its lowest position, and thus move the outer end of the spring 87 into a position in which it will be out of the path of movement of the flange 48 of the truss plate, and thus permit the truss plate to be moved to the left in Fig. 2, when the machine supporting frame has been swung into position to permit the roller 83 to engage the upright flange of the angle bar 84. This construction, consequently, prevents the moving of the machine into the pedestal or compartment unless the roller 83 engages the outer surface of this flange, and thus holds the machine in position in which it cannot be damaged by contact with any parts of the pedestal or compartment while being moved into the compartment and while stored therein. Also, when the machine is withdrawn from the compartment, the roller will prevent the swinging of the machine supporting frame about its pivots 33 and 34 until the roller passes out of engagement with the front end of the angle bar 84 and the spring 87 again prevents inward movement of the truss plate 35, at which time the machine will be clear of the door opening in the front wall, so that no damage to the machine can result from such swinging of the machine supporting frame toward its operative position.

The construction thus far described has the advantage that the various parts of the mechanism can be assembled on the reinforcing plates or strips 57 on a bench or other suitable support where all of the parts are readily accessible, before they are secured in the cabinet. When the various parts are assembled on these reinforcing plates or strips 57, this mechanism may be inserted into a cabinet and the strips 57 secured to the frame members 18 of the cabinet by means of the bolts 59, thus greatly facilitating the assembly of the mechanism.

Suitable means are also provided for securely locking the supporting frame of the machine in its horizontal or operative position and for guiding the frame into this position. In the construction shown for this purpose, a combined stop, locking and guide member is provided in the form of a strike plate 90, one end of which is bolted or otherwise secured to one of the frame members 22, and the other end of which may be bolted to an inwardly extending flange 91 of the front wall 14 of the pedestal or cabinet, see Figs. 5 and 6. This strike plate may have an integral stop 92 formed thereon by partly punching out and bending over a portion of the metal of this plate. This stop is arranged in the path of movement of the frame member 26 and so positioned that when the frame member 26 engages the stop 92, the table top 25 will be in the operative or horizontal position.

A latch or locking device is also provided for holding the table top 25 and its supporting structure in operative position, and for this purpose, the strike plate 90 is provided with a recess or opening 94 into which a locking bolt 95 may ex-

tend to engage with the lower edge of the recess for holding the table top in operative position. The recess 94 is preferably in registration with an aperture in the flange 91 to permit the locking bolt to pass to the desired extent into engagement with the recess and aperture. This locking bolt 95 has a shank 97 guided for movement into and out of locking position in a channel-shaped guide member 96 which is welded or otherwise secured at its ends to the longitudinal frame members 26 and 27 of the machine support. The bolt is slidable within this guide member 96 and may be held against movement through the open rearwardly directed face thereof, for example, by means of pins 98 extending through apertures in the flanges of the channel-shaped member.

The locking bolt is spring-urged into position to enter the notch or recess 94. In the construction shown, a coil spring 99 is employed for this purpose which has two outwardly extending arms. One arm 100 of this spring is formed to enter a pair of apertures in the flanges of the guide housing or channel 96, this arm having one or more bends therein to prevent dislodging of the same from the holes in the flanges when the spring is in operative position. The other arm 101 of the spring engages an end portion 102 of a latch release lever 103, this lever being pivoted at 104 on an extension 105 of the latch guide member 96, this extension being formed by bending a portion of the upper flange of the channel-shaped member 96 upwardly, and providing an aperture therein to receive the pivot member 104 of the release lever. Consequently, the arm 101 of the spring yieldingly urges the release lever 103 into its upper position, shown in Figs. 5, 10 and 11, and causes the locking bolt to swing to the right in Figs. 10 and 11, into engagement with the notch 94 of the strike plate 90. The locking bolt 95 and the stop member 92 are so located that when the frame member 26 swings into engagement with the under surface of the stop member 92, the latch 95 simultaneously moves into engagement with the edge of the notch 94 in the strike plate 90. As a result of this construction, a very secure holding of the table top 25 and its supporting mechanism is made possible, and since the weight of the machine and its supporting frame will exert a downwardly directed force on the locking bolt and an upwardly directed force on the stop projection 92, there will be no lost motion or play between the machine supporting frame and the desk or cabinet.

Means are also provided for suitably guiding the frame member 26 and the parts associated therewith into correct relation for supporting the machine in the desired operative position on the cabinet. For this purpose, the strike plate 90 is provided with a notch or recess 107 extending upwardly from the lower surface thereof and having downwardly flaring sides or edges. This notch or recess is in the path of movement of a bushing 108 arranged about the pivot of the roller 83. The flaring edges of the notch guide this bushing into its seating position in the upper end of the notch, and when in this position, the latch 95 will be in position to engage in the notch 94. This bushing also serves the further purpose of securely holding the machine, the table top and its supporting structure against movement relatively to the pedestal or cabinet so that these parts will be very rigidly supported in their operative positions to avoid vibrations of the

machine and table top during the use of the machine.

When it is desired to swing the table top 25 into operative position after it has been fully withdrawn from the pedestal or compartment, this may be effected by grasping the rail or handle 30 and swinging the machine-supporting mechanism about the pivots 33 and 34 until the bushing 108 enters the notch 107. Further upward movement may cause a slight shifting, either forwardly or rearwardly, of the machine-supporting frame because of the flaring sides of the notch 107, and when the bushing 108 is in its upper position, the frame member 26 will engage the stop 92 and the latch will move into its locking position. When it is desired to lower the machine, it is merely necessary to depress the latch-releasing lever 103 and then swing the machine and its supporting frame downwardly about the pivots 33 and 34.

The mechanism may, of course, be provided with the usual counterbalancing springs to compensate at least in part for the weight of the machine and the pivoted support therefor. Any suitable means for mounting a counterbalancing spring or springs may be provided. In the construction shown, a pair of supporting springs 110 and 111 are provided, the ends of which may be provided with loops adapted to engage cross bars 112 and 113. The cross bar 112 may be secured intermediate of its ends to a bracket member 115 welded or otherwise secured to the truss plate or member 35. The cross bar 113 may be secured to or formed integral with a screw 116 extending through an aperture of the bracket 117 which may be secured to or formed integral with the transverse frame member 28 of the machine supporting frame, as shown in Figs. 1, 2, and 5, and a nut 118 may be provided on the screw 106 for adjusting the tension of the springs 110 and 111 so as to counterbalance to the desired extent the weight of the machine and supporting frame therefor, and thus facilitate the moving of the same into and out of its operative position.

It is, of course, desirable to securely hold the door 15 in its open position while moving the machine into and out of the pedestal or compartment, and for this purpose, I have provided a door stop, shown particularly in Figs. 2, 8 and 9. This door stop includes a strip or bar 120 pivoted at 121 on a bracket or extension 122 suitably secured to the inner face of the door. This bar or strip is slideable on a bracket 124 suitably secured to an inwardly extending flange 125 on the bottom of the door opening in the front wall 14 of the pedestal. The bracket 124 has an upwardly extending flange 126 provided with a slot therein through which the strip or plate 120 extends, and this strip is provided at its inner end with a suitable stop to limit the extent to which the door may be swung into open position, this stop, in the construction shown, being formed by bending over the end of the strip 120 as shown at 127. Consequently, the door can only be swung into open position until the stop 127 engages the flange 126 of the bracket 124.

The door may be yieldingly held in open position by means of a notch or aperture 129 in the strip or bar 120, and a spring-pressed ball 130 mounted on the bracket 124 is yieldingly urged to extend partly into the notch or aperture 129 so as to yieldingly hold the door in its open position. When the door is to be closed, a slight pressure on the door will deflect the ball downwardly out of the notch or hole 129 and permit the strip

or bar 120 to slide through the slot in the flange 126 until the door is closed. Any other suitable means for holding the door in open position and limiting the swinging of the same into open position may be provided, if desired.

It will be understood that various changes in the details, materials, and arrangements of parts which have been herein described and illustrated in order to explain the nature of the invention, 10 may be made by those skilled in the art within the principle and scope of the invention, as expressed in the appended claims.

The term "cabinet" as herein used is intended to apply to a desk or other device having a compartment therein to receive a typewriter or other machine.

I claim as my invention:

1. The combination with a cabinet having a machine compartment, of a rail mounted on a side of said cabinet, a truss member having the lower portion thereof guided for movement lengthwise of said rail and extending upwardly above said rail, a bar rigidly secured to the upper part of said member and extending forwardly beyond said truss member, a machine supporting frame pivoted on said bar, and a guide rail above said first mentioned rail and cooperating with said bar for guiding said bar and truss member for movement into and out of said compartment.
2. A construction according to claim 1, in which a track is provided which is secured to said cabinet and on which said first mentioned rail is mounted for limited movement into and out of said compartment.
3. The combination with a cabinet having a machine compartment, of a rail mounted on a side of said cabinet, a truss member having the lower portion thereof provided with two pairs of rollers, the rollers of each pair being arranged one above the other, said rail extending between the rollers of said pairs and having its upper and lower surfaces formed to cooperate with said rollers, a track secured to said cabinet and on which said rail is mounted for lengthwise movement, stop means for limiting the extent of movement of said member on said rail and said rail relatively to said track, and a machine supporting frame mounted to swing relatively to said member.
4. The combination with a cabinet having a machine compartment, of a truss member having a rigid bar secured to the upper portion thereof, means on said cabinet for guiding said bar for movement in the direction of its length, a machine supporting frame pivotally mounted on said bar to swing about a pivotal axis which is substantially parallel to said bar, and a guide rail on which the lower portion of said truss member is guided for movement thereof into and out of said compartment, said guide rail supporting the entire weight of said truss member, bar and parts mounted thereon and having upper and lower surfaces on which said truss member bears to hold said bar in substantially horizontal position during its movement into and out of said compartment.
5. The combination with a cabinet having a machine compartment and a machine supporting frame, of a carriage of substantially cantilever shape having a forwardly extending part on which said machine supporting frame is hinged to swing about an axis extending lengthwise of said compartment, a rail on which the lower part of said carriage is mounted to move lengthwise of said compartment, said rail being located in the lower

portion of said compartment, and a guide rail arranged in the upper portion of said compartment in spaced relation to said first mentioned rail and with which the upper portion of said carriage cooperates to hold said carriage in upright position.

6. The combination of a cabinet having a machine compartment and provided at one side thereof with upper and lower guides and a rail arranged intermediate of said guides, a truss member movable at said side of said compartment lengthwise of the same and having the lower portion thereof supported by and movable on said intermediate rail, a part on said truss member engaging said upper guide to maintain said truss member in upright position, a supporting frame for a machine pivotally mounted on the upper portion of said truss member to swing into a vertical and a horizontal position, said lower guide having an upright flange spaced from said side of said compartment, and a part on said frame arranged to enter into the space between said upright flange and said side of said compartment when said supporting frame is in vertical position to hold said frame member against swinging out of a substantially vertical position when said truss member is moved lengthwise of said cabinet.

7. The combination with a cabinet having a machine compartment and a machine supporting frame, of a carriage on which said machine supporting frame is mounted to swing into a lower position for entry into said compartment and into an upper operative position, a rail on which said carriage is mounted to move into and out of said compartment, a track secured to said cabinet and on which said rail is mounted to move in a direction parallel to said carriage, said rail having its upper and lower edge portions of V-shaped cross section to form inner trough-shaped portions, said track having outwardly facing trough-shaped grooves, rolling members in said trough-shaped portions of said track and rail, wheels on said carriage engaging the upper and lower edge portions of said rail, and stop members on said carriage, said rail and said track to limit the movement of said carriage relatively to said compartment.

8. The combination with a cabinet having a machine compartment and a machine supporting frame, of a carriage movable into and out of said compartment and on which said frame is hingedly mounted to swing into a lower position to enter said compartment and upwardly into an upper position when said carriage is in its outer position with reference to said compartment, a member mounted on said cabinet and extending into the path of movement of said carriage into said compartment when said frame is swung out of its lower position, and means on said frame for moving said member out of its position in the path of movement of said carriage when said frame is in its lower position to permit said carriage and frame to move into said compartment.

9. The combination with a cabinet having a machine compartment and a machine supporting frame, of a carriage movable into and out of said compartment and on which said frame is hingedly mounted to swing into a lower position to enter said compartment and upwardly into an upper position when said carriage is in its outer position with reference to said compartment, a guide rail in the lower part of said compartment, a part on said frame arranged to cooperate with said guide rail when said frame is in its lower

position and when said carriage is moved into said compartment to hold said frame against swinging out of its lower position when in said compartment, a detent member mounted on said cabinet and extending into the path of movement of said carriage to prevent movement of the same into said compartment when said frame is swung out of its lower position, and a part on said frame which engages said detent member when said frame is in its lower position to permit movement of said carriage into said compartment.

10. The combination with a cabinet having a machine compartment and a machine supporting frame, of a carriage movable into and out of said compartment and on which said frame is hingedly mounted to swing into a lower position to enter said compartment and upwardly into an upper position when said carriage is in its outer position with reference to said compartment, a guide rail in the lower part of said compartment, a part on said frame arranged to cooperate with said guide rail when said frame is in its lower position and when said carriage is moved into said compartment to hold said frame against swinging out of its lower position when in said compartment, a spring mounted on said cabinet and extending into the path of movement of said carriage into said compartment when said frame is swung out of its lower position, and a part on said frame arranged to engage said spring when in its lower position to permit said carriage to move into said compartment.

11. The combination with a cabinet having a machine compartment, of a rail mounted on a side of said cabinet, a truss member having the lower portion thereof guided for movement lengthwise of said rail and extending upwardly above said rail, a bar rigidly secured to the upper part of said member and extending forwardly beyond said truss member, a machine supporting frame pivoted on said bar, a bracket secured to said truss member and extending upwardly above the same, and a counterbalancing spring connected at one end to the upper portion of said bracket and having the other end secured to said frame for exerting an upward pull on said frame.

12. In a cabinet having a machine compartment and a machine supporting frame movable into and out of said compartment while in substantially vertical position and which may be swung into a substantially horizontal position while out of said compartment, that improvement which includes a strike plate secured to said cabinet and having a stop thereon which extends into the path of movement of said frame when the same has been swung into a substantially horizontal position, said strike plate having an opening therein, a latch member on said frame and positioned to enter said opening when said frame strikes said stop, said latch releasably holding said frame in said substantially horizontal position, and interengaging parts on said strike plate and said frame for guiding said frame into correct operative relation to said cabinet, including a recess in the lower edge of said strike plate and a projecting part on said frame formed to enter said recess when said frame is in correct relation to said cabinet.

13. A construction according to claim 12, in which said recess in said strike plate has downwardly and outwardly flaring side edges, said flaring side edges when engaging said part on said frame serving to shift said frame into correct relation to said cabinet.

14. The combination with a cabinet having a machine compartment and a machine supporting frame, of a carriage on the upper portion of which said machine supporting frame is mounted to swing into a lower position for entry into said compartment and into an upper operative position, a rail on which the lower portion of said carriage is mounted to move into and out of said compartment in a direction lengthwise of said rail, a track secured to said cabinet and on which said rail is mounted to move in a direction parallel to the movement of said carriage, cooperating stops on said carriage, said rail and said track for limiting the movement of said carriage and said rail into and out of said cabinet, an upper guide secured on said cabinet in spaced relation to said rail and track, and a part on the upper portion of said carriage engaging said guide for holding said carriage in upright position and in correct relation to said rail during the movement of said carriage in said compartment.

15. The combination with a cabinet having a machine compartment and a machine supporting frame, of a carriage on the upper portion of which said machine supporting frame is mounted to swing into a lower position for entry into said compartment and into an upper operative position, a rail on which the lower portion of said carriage is mounted to move into and out of said compartment in a direction lengthwise of said rail, a track secured to said cabinet and on which said rail is mounted to move in a direction parallel to the direction of movement of said carriage, wheels mounted on said carriage and engaging upper and lower surfaces of said rail, rolling parts interposed between said track and said rail, an upper guide secured on said cabinet in spaced relation to said rail, and a part on the upper portion of said carriage engaging said

guide for holding said carriage in upright position and in correct relation to said rail during the movement of said carriage lengthwise of said rail.

- 5 16. In a cabinet having a machine compartment provided with an opening therein through which a machine may be moved into and out of said cabinet, a plurality of upright frame members forming a part of a side wall of said cabinet, 10 a carriage, a machine supporting frame hingedly mounted on said carriage, guide members lengthwise of which said carriage is movable, and a plurality of upright reinforcing members of less height than said opening and on which said 15 guide members are rigidly secured with said carriage and machine supporting frame mounted thereon, and means connecting said upright reinforcing members to said upright frame members of said cabinet after said carriage, said guide members and machine supporting frame are assembled on said reinforcing members.

FLOYD H. BLOOMSTRAN.
